CLAIM

The ornamental design for an illuminated indicator wall switch, as shown and described.

DESCRIPTION

FIG. 1 is a top right and front perspective view of an illuminated indicator wall switch showing my new design;

FIG. 2 is a rear elevational view thereof, the front elevational view thereof being a mirror image;

FIG. 3 is a left elevational view thereof; and,

FIG. 4 is a bottom plan view thereof.

*Fig. 2**Fig. 3**Fig. 4*
